DESIGN FOR A DISPLAY CASE

Albert M. Travis, Kansas City, Kans., assignor to
John C. Hockery, Kansas City, Mo., trustee

Application July 26, 1947, Serial No. 140,536

Term of patent 14 years

(Cl. D80—11)

To all whom it may concern:

Be it known that I, Albert M. Travis, a citizen of the United States, residing at Kansas City, in the county of Wyandotte and State of Kansas, have invented a new, original, and ornamental Design for a Display Case, of which the following is a specification, reference being had to the accompanying drawing, forming part thereof, in which

Fig. 1 of the drawing is a perspective view of a display case showing my new design, and

Fig. 2 of the drawing is a perspective view of the display case shown in Fig. 1 showing same from the opposite side.

I claim:

The ornamental design for a display case, substantially as shown.

ALBERT M. TRAVIS.
